CLAIM

The ornamental design for a hook plate, as shown and described.

DESCRIPTION

FIG. 1 is a front perspective view of a hook plate comprising the new design;

FIG. 2 is a bottom perspective view of the design of FIG. 1; FIG. 3 is a top view of the design of FIG. 1;

FIG. 4 is a bottom view of the design of FIG. 1; FIG. 5 is a right side elevational view of the design of FIG. 1;

FIG. 6 is a left side elevational view of the design of FIG. 1; FIG. 7 is a front elevational view of the design of FIG. 1; and,

FIG. 8 is a back elevational view of the design of FIG. 1. The broken lines shown in the figures are directed to the environment and are for illustrative purposes only; the broken lines form no part of the claimed hook plate invention.

The relatively light intermittently broken surface shading depicts contour, not surface decoration.
